CLAIM

The ornamental design for a vegetable container as shown and described.

DESCRIPTION

FIG. 1 is a rear, left perspective view of a vegetable container shown with environmental subject matter; FIG. 2 is a front, right perspective view thereof; FIG. 3 is a front, left perspective view of the vegetable container shown with the door in an open configuration; FIG. 4 is a bottom, right perspective view of the vegetable container with the door closed and without the environmental subject matter;

FIG. 5 is a front view thereof;

FIG. 6 is a left view thereof;

FIG. 7 is a right view thereof;

FIG. 8 is a top view thereof; and,

FIG. 9 is a bottom view thereof.

The portions of the vegetable container shown in broken lines form no part of the claimed design. The broken line showing of a jar and plant is for the purpose of illustrating environmental subject matter and forms no part of the claimed design.

1 Claim, 8 Drawing Sheets
